UNITED STATES PATENT OFFICE.

CHARLES P. HIDDEN, OF BROOKLINE, MASSACHUSETTS, ASSIGNOR TO THE LAMSON COMPANY, OF BOSTON, MASSACHUSETTS, A CORPORATION OF NEW JERSEY.

COIN-HANDLING APPARATUS.

1,143,827.

Specification of Letters Patent. Patented June 22, 1915.

Application filed October 20, 1913. Serial No. 796,229.

To all whom it may concern:

Be it known that J. CHARLES P. HIDDEN, a citizen of the United States, residing at Brookline, in the county of Norfolk and 5 State of Massachusetts, have invented certain new and useful Improvements in Coin-Handling Apparatus, of which the following is a specification.

This invention relates to coin-handling 10 apparatus and more particularly to that class of apparatus of this general description which has been designated multiple deliverers.

One of the objects of my invention is to 15 provide a very simple and improved mechanism whereby upon the pressure of the finger or the like upon a button or key, an amount of change will be automatically ejected or dislodged from one or more compartments, as the case may be, of a coin tray or receptacle.

I have further aimed to so construct the 20 said apparatus that the base thereof will occupy but a small amount of, for example, counter space; which feature is extremely desirable where apparatus of this description is used in stores, banks and the like.

Another object of my invention has been 25 to so construct the apparatus that the said coin tray when removed from the ejecting mechanism proper, will be substantially devoid of movable parts.

I have further aimed to produce a mechanism of the character in question in which 30 the number of parts may be held at substantially a minimum; at least in view of the requisite compactness, ease and certainty of operation.

I have also provided means whereby, if 35 desired, but forty nine keys may be provided in combination with a special auxiliary lever to enable the operator to make change up to one dollar and indeed more than this amount, with practically no more effort upon his part for amounts up to one dollar than is required in machines of this description, as usually made, in which a bank of one hundred keys is used.

These and other objects of my invention 40 will be hereinafter referred to and the novel elements and combination of elements whereby the same may be attained will be more particularly pointed out in the claims appended hereto.

55 In the accompanying drawings which

form a part hereof I have exemplified preferred forms of my apparatus; but as I am aware that various changes and modifications may be made therein within the purview of my invention and without departing from the spirit thereof, I desire to be limited only by the scope of said claims.

Referring to the drawings: Figure 1 is a substantially vertical section of a preferred type of the apparatus in question; the said section being taken on the line 1-1 of Fig. 2. Fig. 2 is a front elevation of said apparatus partly broken away for convenience in illustrating; the coin tray also being removed for the same reason. Fig. 3 is a top view of the preferred form of coin tray. Fig. 4 is a fragmentary detail of the corner of one of the rock frames or plates. Fig. 5 is a detail rear view of the coin releasing flap or lever together with the associated lever which also controls the ejection of 50¢ pieces or the like. Fig. 6 is a diagrammatic vertical section of a modified construction. Fig. 7 is a detail fragmentary view of a lower corner of a modified rock frame or plate.

The casing 1 may be of any suitable material and construction adapted to support and contain the operating parts, or most of the same, and comprises a base 2 to which is suitably fastened a sheet metal frame 3, the lateral walls of which may be provided with recessed lugs 4' for the reception of the several transverse rods which carry the rock frames hereinafter referred to, and like parts.

The sloping top 3' of the casing may, if desired, be a plate separate from the frame 1 suitably secured thereto in any desired manner as indicated in Fig. 1 and the front 4 of the casing is also preferably made separate and may be secured to the said lateral walls by means of angular clips 5 and 6. Thus also, if desired, the lateral, rear, front and top walls may all be made 100 of sheet metal, bent to the desired configuration, and suitably riveted or clipped together.

The front wall is apertured in the upper and preferably rearwardly sloping portion 105 thereof for the reception of the key-operated elements or push bars 7; these bars being stamped or cut out of sheet metal and being rectangular in cross section; the slots 8 for the reception of the same in the said front 110

plate snugly fitting said bars so as to permit of guided longitudinal movement of the latter. Each of these push bars carries a key or button 9 which is preferably correspondingly numbered to the amount of money, in cents, which pressure upon such button will effect the ejection of from the tray 10. It will be observed that in the preferred form of my device but 49 such buttons are provided; they together with the lever hereinafter referred to, affording control of sums ranging from one cent to one dollar or more.

The tray 10 is preferably a casting having in the front thereof pockets adapted for the reception of coins of various denominations. Preferably, as shown in Fig. 3, the two left hand pockets are adapted to retain dimes or ten cent pieces. The next pocket or compartment from the left is adapted to hold quarters or twenty-five cent pieces; the next for half dollars or fifty cent pieces; the next, nickels or five cent pieces and the remaining three, stacks of pennies.

The coin compartment walls are substantially cylindrical and the coins may be inserted thereinto freely from the top; the bottom coin normally reposing in each case upon a suitable ledge, or rather ledges 12, since a slot 13 extends transversely across the bottom through each of these latter and is adapted to form a guide way for the coin ejectors 14. These latter have preferably somewhat the form of a shallow U; and as viewed in Fig. 1, the short left hand upwardly extending arm 15 of the U constitutes the part which actually engages a given coin. Preferably this part is sloped down rearwardly from its highest and foremost point to facilitate the retraction of the ejector when the part 15 is being pulled back in contact with and depressed by the bottom of the lowermost coin in the corresponding pocket.

The right hand arm 16 of each ejector has pivotally connected thereto, as at 17, the ear like extremities of its actuating lever 18. Each of the latter is pivoted at 19 to a suitable bracket 20 which may be secured to the front plate 4 in any desired manner, as by projecting the forward end of each of said brackets into suitably sloping walled slots 21 in said front plate and peening said ends to form a dove-tail connection.

Each lever 18 is substantially U shaped in cross section and hence is adapted for the reception of the flat bracket 20 which supports the same; while its eared lower extremities straddle or embrace the ejectors 14 in the manner above indicated. The upper and similarly eared extremity of each lever 18 is pivotally connected to a flat link 22 and the other extremity of each such link is in turn pivotally connected at 23 to ears 24 which may, if desired, be punched for-

wardly out of the corresponding rock frame or grid 25. These rock frames or plates are all identical in construction and have preferably superimposable apertures, with the exception of the provision of specially located holes 26 therein for the reception of rods 27, of which there is one for each ejector; the forward extremities of the rods 27 being pivotally connected at 28 to the respective arms 16 of the ejectors. Each rod 27 is normally held in its rearmost position by corresponding coil springs 29; these springs being substantially all in the same practically horizontal plane, and having their rear extremities connected to an angle bar 30 which is fastened to the rear wall of the casing.

It will be noted that by reason of the construction shown, each spring 29 not only serves to retract its corresponding ejector 35 but further serves to retain the upper straight edge 31 thereof in contact with the guiding wall 32 of the slot 33 provided opposite the middle of each coin pocket adjacent the lower edge of the front plate 4. Hence the coin ejecting nose or nib 15 is forced to move in guided relationship to the bottommost coin in the corresponding repository or pocket, which insures a proper ejection of said coin from the latter.

The levers 18 are normally all disposed in substantially the same vertical plane but since the grids or frames 25 are arranged successively one behind the other, the links 22 which connect the respective levers and frames are made increasingly longer, preferably as the left hand side of the apparatus is approached, viewing said apparatus as in Fig. 1. Of course the plates or grids 25 will be slotted, as at 34, for the reception of these links; but such slots may be made sufficiently long to accommodate the somewhat irregular disposition of said links, which avoids special punching of the grids in such portions thereof.

It will be understood, further that while the first plate will have six links extending therethrough, each succeeding plate back will have one less link projecting through it, so that a number of slots 34 will be idle. Similarly, while for convenience of manufacture a grid may, if desired, have the ears 24 thereof struck up in correspondence with the spaces between the centers of the coin pockets, across substantially the entire width 110 of said plate; but one pair of such ears will be actually connected to a link for any given plate. In fact absolute uniformity of said plates may be had if a single slot or rather, in this case, extended recess 26 be provided in the bottom of each plate or grid which shall be deep and wide enough to accommodate the reception of all the springs 29 in the rearmost plate, as in Fig. 7, wherein a lower corner of such a frame is

shown; said frame being designated 35. The plates or frames 25 or 35, as the case may be, may conveniently be mounted upon a series of fixed rods 36; and in the preferred construction there are 7 of such rods disposed in a plane which is preferably oblique to the horizontal, owing to the oblique disposition of the push rods 7, which latter facilitates the reading of the numerals upon the buttons or keys. The extremities of the rods 36 are received into suitable recesses in the lugs 4, above referred to.

Referring to Fig. 1, it will be noted, that the respective push bars are adapted for longitudinal movement through their corresponding apertures 8 in the front plate 4, as above noted; while the inner ends of these bars are correspondingly guided and held against lateral displacement by an apertured plate 37. This plate covers a correspondingly recessed block 38 which may conveniently be made of wood if desired and which is fastened in any suitable manner to the sloping portion 39 of the casing. The recesses 40 in the block 38 correspond in number and disposition with the buttons 9 and each of these recesses, of which in the present case there are 49, contains a light helical or coiled spring 41, the inner end of each of which may bear against a suitable washer or plug 42 of fiber or the like, while the outer or forward ends of these springs may bear against washers 42' seated upon the reduced extremities 43 of the corresponding elements 7.

Each of the bars 7 may be held in its proper position so as to maintain its corresponding spring 41 under suitable compression by a lug 44 which is normally held in contact with the inner or underside of the front plate 4 by said spring and which, hence, limits the outward movement of its rod or bar. Each of the bars 7 carry one or more lugs or shouldered parts 45; and each of these lugs is adapted for engagement with one of the frames 25. Thus, the button 49 which controls the uppermost rod 7 shown in Fig. 1 is adapted to control the rocking of five grids 25. These grids may be conveniently arranged to control the ejection of coins as follows:

The right hand plate in Fig. 1 dominates the left hand or dime repository of the tray shown in Fig. 3, and when this plate is rocked, its link 22 swings the lever 18 which controls the ejector 14 which is adapted to shove a dime from said left hand pocket of the tray. Similarly the next frame 25, going toward the left in Fig. 1, controls the ejection of dimes from the next pocket, going to the right, in Fig. 3. The third frame 25, from the right in Fig. 1, controls the ejection of quarters from the third pocket from the left in Fig. 3. The fourth frame 25, from the left of Fig. 1 controls the ejection

of nickels from the fifth pocket from the left in Fig. 3. The fifth frame from the left in Fig. 1 controls the ejection of pennies from the third pocket from the right in Fig. 3; and it may be here noted, that the nose 15 of the ejector for this pocket extends up into said pocket sufficiently to effect the ejection of two pennies at one time. Similarly the sixth frame from the right in Fig. 1 controls the ejection of two pennies at a time from the second coin pocket from the right in Fig. 3, while the most left hand frame 25 in Fig. 1 controls the ejection of single pennies from the right hand coin pocket of the tray, as viewed in Fig. 3. It will be seen, therefore, that in order to effect the ejection of 49¢ from the tray the five lugs 45 upon the corresponding element 7 will respectively engage the three right hand frames 25 in Fig. 1, controlling the ejection of two dimes and a quarter of a dollar, and the second and third frames 25 from the right in said figure, each of which controls the ejection of two cents at a time; giving a total sum of 49¢. In like manner the button marked 1 is disposed upon a bar 7 which has but a single lug 45 and that adapted to control the left hand frame 25 in Fig. 1, and so on.

Since the leverage changes slightly in going from the upper tier of buttons to the lower tier of the same, if desired, the springs 41 of the uppermost tier may be made slightly stronger or stiffer than those for the next lower tier and so on grading down to provide the lightest springs for the lowermost row of buttons.

The plugs 42 may be of graded thickness, if desired, according to the remoteness of the row in which they are disposed from the pivotal axes of the grids. This provides for successively shorter springs which may be correspondingly stiffer; while the reduced extremity 43 of each of the bars 7 may be made of sufficient length to insure the abutment of said extremity against the corresponding lug 44 and thereby provide a stop for said bar. It is evident that the button bearing the numeral 1, which will actuate the left hand frame 25, needs less travel to effect the ejection of the coin controlled thereby than does the button marked 46, for example, in the upper row of said buttons, and the graded stops for the push bars hence prevent undue rotation of any given grid, no matter by what element 7 such grid be actuated.

The buttons may be conveniently screwed or otherwise secured upon the outer reduced extremities 46 of the bars 7, as by means of cement, or the like, after the mechanism has been assembled.

The coin tray is preferably provided with lugs 47 upon the back thereof into which may be screwed shoulder screws 48 and the

heads of these screws are entered into the enlarged or circular portions of key-hole-like apertures 49 in the lower portion of the front plate 4; the shanks of the studs 48 dropping down into the reduced portions 50 of said openings and thereby holding the said tray firmly in place.

The coin tray is adapted to retain coins therein in stacks and to hold such coins 10 against inadvertent displacement. It is preferably disposed somewhat at an angle to the perpendicular and the bottoms of each of the ribs 51 are cut away, as at 52, to permit of the egress of but one coin at a 15 time in each case with the exception of the two columns from which it is intended to eject two pennies at a time.

In front of the trays is a hopper 53 shaped preferably substantially as shown 20 in Figs. 1 and 2; and it will be observed that the rear wall 54 of this hopper slopes forwardly toward the front wall 55 and has its bottom edge sufficiently close to said front wall 55 to prevent even dimes from falling 25 completely over flatwise. In other words, every coin ejected which is capable of impinging against the sloping lateral walls 56 of the hopper is so guided thereafter that it will in all instances roll down said sloping wall for a portion, at least, of the 30 length of the latter; which expedites the delivery of said coin.

The coins deposited in the hopper will, if the flap or coin retaining or holding means 35 57, which closes the opening in the bottom thereof, be not closed, emerge through said opening; but this closure is normally retained in its closed position by means of a coiled spring 58 mounted upon the rod or 40 shaft 59 upon which is pivoted the said flap.

The preferred construction of flap is that shown in Fig. 1 wherein it is made of sheet metal looped around to provide a bearing 45 for the reception of the shaft 59 and having one of its sides adapted to extend out substantially horizontal to close the opening in the bottom of the hopper; while its other side 60 extends downwardly, preferably slightly forward from the perpendicular, to 50 provide an actuating lever for the closure.

As best shown in Fig. 5, the spring 58 is received in a recess 61 cut or slotted through the bearing portion of the flap; one end of the spring 58 being secured to the shaft 59, 55 which latter is preferably fixed in any suitable manner. A somewhat U-shaped operating lever 62 is also loosely mounted upon this shaft and both it and the flap may be held against longitudinal displacement with 60 respect to said shaft by pins 63, or the like. The provision of this lever is believed to be distinctively novel since when pushed back by the finger or fingers of the operator it not only opens the hopper closure 57 by reason of the engagement between the lower ex-

tremity of the operating arm 60 of the latter but further drives rearwardly a link 63 which is pivotally connected at 64 to suitable ears mounted upon substantially the median line of the U shaped lever; and this 70 link in turn rocks the lower arm 65 of a lever mounted upon a fixed shaft 66 and thereby swings the upper arm 67 of said lever forwardly. The upper extremity of the arm 67 may have a slotted connection 75 with the pin 17 of the lever 18 which corresponds to the pocket containing 50¢ pieces; but which lever in this case need have no link 22. Pin 17 in this particular instance is sufficiently extended so that the ends thereof 80 may ride in the slots at the upper extremities of the bifurcated arm 67. Hence when the lever 62 is pushed inwardly it effects the ejection of one 50¢ piece, per actuation, 85 from the corresponding receptacle; and as many of said pieces may be ejected into the hopper as may be required to make up the desired amount, when the latter is over one dollar, by successively actuating lever 62 the required number of times.

In order that the finger of the operator may not inadvertently come into contact with the lever 62 when it is simply intended to operate the closure 57 alone, the bottom of the flap arm 60 of the latter may be 90 looped out at 69 to provide a stop which the finger is practically certain to feel and which further prevents the finger from slipping downwardly along the lever 60 as the latter is pushed inwardly. On the other hand, when it is desired to actuate the closure 57 and to simultaneously eject a 50¢ piece the curved conformation of the bottom 95 of the lever 62 together with its disposition below projection 69 of the flap 60, insures 100 the operator's engagement of said lever 62 by the sense of touch. To further facilitate the actuation of this latter, a part of the lever 62 preferably is made to swing in a recess 70 provided in the base 2 of the casing; so that when the fingers of the operator are 105 inserted below the hopper so that they are directly or almost in contact with the surface of the counter or table upon which the mechanism rests, they will encounter lever 110 62 alone, while on the other hand when the operator's fingers clear the counter by a moderate amount and are inserted almost immediately below the closure 57, they will 115 actuate only the latter; the arm 60 swinging backwardly away from the arm 62 and the fingers entering the oval space 71 in 120 said lever.

It will be noted that the stack of 50¢ pieces is almost immediately over the center 125 of the opening in the hopper so that coins ejected from this stack drop immediately and directly into the hand of the operator; no time being lost by causing such coins to roll down the slot 56.

The general mode of operation of the mechanism may now be briefly described: Assuming that the coin tray is in place upon the front plane 4 and that its 5 pockets have been filled with coins of the indicated denominations; now if the amount of change required be less than 50¢ the operator pushes the corresponding button which, let us say, is 40. This effects a 10 longitudinal displacement of the corresponding push bar against the action of its spring and as this bar carries three lugs 45 one of which is adapted for engagement with the right hand or ten cent frame 25; 15 the second of which is in engagement with the twenty-five cent controlling frame, *i. e.* the third from the right; and the third of which will displace the five cent controlling frame next adjacent to the latter, to the left, 20 said three frames will hence be rocked and their respective links 22 will swing the corresponding levers 18 and thereby effect the ejection of one 25¢ piece, one dime and one 5¢ piece or nickel, making the required 40¢. 25 This money will immediately drop into the hopper 53 and may be removed therefrom at the convenience of the operator by pressing inwardly slightly upon the flap arm 60. It may be noted in this connection that 30 owing to the fact that all of the coins, when in contact with closure 57 are angularly disposed with respect to the same and by reason of the rearward slope of the wall 54 and perpendicular wall 55 of the hopper, such coins will have their forward extremities in contact with the bottom of the wall 55 and but a slight movement of the flap arm 60 suffices to allow them to drop out: 35 whereas if some or all of these coins rested flatwise upon the closure 57 the latter would have to swing downwardly approximately through 40 or 45 degrees, if it were horizontally disposed; before all of the coins could freely drop out. It is more desirable to 40 have the said closure 57 substantially horizontal since if it be set at a considerable angle the dropping coins would have a tendency to wedge it open and hence force their way out; or otherwise a much stronger spring 58 would have to be provided or 45 some similar provision made. If now it be desired to eject 90¢ instead of 40¢, as for example, if a 10¢ purchase has been made and a dollar has been tendered to the clerk, 50 the clerk again presses the 40¢ button which deposits 40¢ in change in the hopper; but in this case instead of keeping the fingers well clear of the counter, the clerk drops them down toward the latter until they just 55 graze it, when his fingers will obviously encounter the lever 62 and this lever when swung backwardly effects the ejection of the 60 50¢ piece in the manner above described, this coin augmenting those in the hopper to 65 make a total of 90¢, the desired change;

which drops down into the fingers or palm of the operator. If a two dollar bill had been tendered for the 10¢ purchase, the 40¢ button would have been pressed and instead of merely swinging back the lever 62 a single time, such lever would be operated thrice: each actuation thereof dropping 50¢ into the palm of the operator, who would hence have drawn \$1.90 from the mechanical cashier. 75

It only remains to be added that after the ejection of any given coin from its corresponding pocket by its ejector, the column or stack of coins in said pocket immediately drops and presses down the nose 15 of the 80 said ejector by substantially the width of the coin or coins ejected from said pocket; the corresponding spring 29 yielding very slightly to permit of this action; but as it is already under tension the instant that the 85 corresponding button or lever 62, as the case may be, is released, said spring retracts such ejector so that it clears the next coin above, whereupon the nose 15 is snapped up back of this coin, or if there be two coins to be 90 ejected, said two coins, preparatory for the next operation of the mechanism. If the button has been pressed to effect the desired ejection of change to the hopper, the corresponding spring 41 pushes the bar 7 of such 95 button out to its normal position as soon as the finger is removed from the key.

In Fig. 6 I have shown a slight modification of the mechanism in question, somewhat diagrammatically. In this case instead of pivoting the rock frames or grids at their lower extremities, said frames have been pivoted substantially at the centers thereof, as at 36' with the exception of the frame or element which controls the ejection of 50¢ pieces; which in the present instance has been designated 72 and which is pivoted at its upper side or end. Herein the links 22 and ejectors have been virtually combined into a single element in each case, the ejector proper 15' having its body portion 14' directly pivoted at 73 to the lower side of the corresponding rock frame 25''. Here, as in the case of the links 22, the length of the link proper 14' will vary according to the distance back from the coin tray to the corresponding rock frame. It will be understood that in this figure, owing to its diagrammatic character, lines have been used wherever practicable to represent extended parts. A lug 74 upon each of the members 14' has pivotally connected thereto a rod 27' which in turn is connected to a spring 29', so that the latter normally retracts all of the ejectors and holds the rock frames in 110 their proper normal positions, as in the previously described mechanism. 115

The special mechanism for ejecting 50¢ pieces may be substantially the same as in the preceding case save that the operating 120

arm 67 which extends upwardly from the shaft 66, is linked directly back to the lower extremity of the frame or element 72 by a connection 75.

5 Other parts in this modified construction which are similar in form, and function to corresponding parts in the mechanism shown in Fig. 1 have been correspondingly designated and need not be further described.

10 The mounting of the ejectors independently of the coin tray is of considerable advantage since it permits of the removal of said tray and the placing of it, when desired, upon its back on a counter or the like 15 without the possibility of the inadvertent ejection of coins therefrom by said ejectors; while by thus mounting all operative parts within the casing a very compact and practical construction is otherwise afforded.

20 The advantage of thus providing means for ejecting a coin, of preferably relatively large denominations, by the same movement which frees the smaller change from the hopper is a considerable one in that it permits of the reduction of the number of keys to a minimum; in the exemplified construction but 49 of such keys being provided, and this number sufficing to make change up to practically any desired amount. It will 25 hence be seen that the number of parts in my construction are reduced substantially to a minimum while the cost of manufacturing is relatively but small.

It is preferred to use sheet metal practically throughout owing to the facility with which parts may be stamped or struck up out of such material while at the same time affording adequate rigidity to such parts. In this connection it may be noted that practically all parts made of sheet metal which are subjected to bending stresses have either been disposed edgewise to the stress, as in the ejectors 14, or have been flanged as in the case of the rock frames and levers 18.

40 The substantially vertical disposition of the grids materially favors the construction of the mechanism with a small base, which is extremely desirable where said mechanism is emplaced upon store counters, and the 45 like.

In conclusion I desire to point out the utility of a novel detail of construction. The arm 65 is elbowed, as shown in Fig. 1, so that the bend 76 therein constitutes a stop 50 for the flap arm 60, when the closure 55 is actuated alone; the rearward thrust upon arm 60 being sustained by the part of the arm 65 between its bend 76 and rod 66 in such manner that there is practically no 60 tendency to rotate arm 65.

Having thus described my invention what I claim is:

1. In a coin handling mechanism, a series of keys, a series of grids, supporting elements for the latter, pivotal connections be-

tween said grids and elements to permit of free movement of said grids with respect to each other, key operated selective means for swingingly displacing one or more of said grids in accordance with the keys actuated, 70 a coin receptacle, and means controlled by said grids for ejecting coins of different denominations from said receptacle in accordance with the grids operatively displaced.

2. In a coin handling mechanism, a series 75 of keys, a series of pivotally mounted grids, key operated elements normally extending through said grids and having parts adapted to selectively engage said grids whereby to swing the latter, a coin receptacle, and 80 means actuated by said grids for effecting the displacement of coins from said receptacle.

3. In a coin handling mechanism, a series 85 of grids, a series of bars normally extending through said grids and adapted for movement in the direction of the length of said bars, said bars having shouldered parts for selectively displacing said grids by pressure thereagainst when said bars are displaced in 90 the direction of their length, coin compartments, and means controlled by said grids for effecting the displacement of coins from said compartments.

4. In a coin handling mechanism, a series 95 of keys, a series of pivotally mounted apertured plates, a series of bars normally extending through the apertures in said plates, said bars having shoulders for selectively rocking said plates by pressure thereagainst 100 when said bars are operated, coin compartments, and a series of means each of which is controlled by one of said plates, for effecting the displacement of coins from said compartments.

5. In a coin handling mechanism, a series of keys, a series of substantially vertically disposed apertured grids relatively movable with respect to each other, means extending through the aperture of said grids for selectively moving said grids in accordance with the key actuated, coin compartments, the axes of which extend in substantial parallelism with the general planes of said grids, means controlled by said grids for 110 effecting the displacement of coins horizontally from said compartments, and a casing for said grids adapted to occupy but relatively small space when placed upon a counter, said substantially vertical disposition of said grids permitting of said small base.

6. In a coin handling mechanism, a series of keys, a series of pivotally mounted grids, a series of elements normally extending through said grids and having means adapted to selectively actuate the same, a series of coin compartments or receptacles, a series of coin ejectors, a series of levers to which said electors are pivotally connected, 125 130

and a series of springs each of which is individually adapted to normally hold the corresponding ejector both upwardly toward its coin compartment and outwardly toward 5 a side thereof, said springs further individually adapted to swing both said levers and said grids into determined and normally occupied positions.

7. In a coin handling mechanism, a series 10 of keys, coin repositories, means for selectively effecting the displacement of coins therefrom in accordance with the key actuated, means to receive the displaced coins, means for releasing said displaced coins 15 from said last mentioned means, an additional coin repository, and means independent of said series of keys, for causing a coin to be displaced from said additional coin repository and to be added to the coins 20 placed by said first mentioned means, said independent means having a portion thereof adapted to operate said releasing means.

8. In a coin handling mechanism, a coin 25 hopper having means to normally retain coins therein, means for freeing said coins and means to directly co-act with a part of said coin freeing means to add an additional coin to said freed coins as the latter are released from said hopper.

30 9. In a coin handling mechanism, coin repositories, means for effecting the displacement of coins therefrom, means to receive and hold said coins, and mechanical means to release said coins from said holding means 35 while adding a coin of determined value thereto.

10. In a coin handling mechanism, coin repositories, means for effecting the displacement of coins therefrom, means to receive 40 and hold said coins, means movable independently to release said coins, and means adapted to co-act with said last mentioned means to release said coins while adding a coin of determined value thereto.

45 11. In a coin handling mechanism, a series of coin repositories, means for effecting delivery of coins therefrom, means for receiving and holding said delivered coins, and mechanical connective means for augmenting the number of said coins while releasing the same from said holding means.

50 12. In a coin handling mechanism, a receptacle into which coins are delivered, said receptacle adapted to retain said coins therein, in combination with mechanical connective means for effecting a delivery of said

coins from said receptacle while substantially simultaneously augmenting the number thereof.

13. In a coin handling mechanism, a receptacle into which coins are delivered, a releasing part for delivering said coins from 60 said receptacle, a coin repository, and mechanical connective means for simultaneously actuating said releasing part and ejecting a coin from said repository.

14. In a coin handling mechanism, a receptacle into which coins are delivered, a releasing part for delivering said coins from 65 said receptacle, a coin repository, and means for simultaneously actuating said releasing part and ejecting a coin from said repository, said releasing part adapted for independent actuation, and a part of said last mentioned means being adapted to act as a 70 stop for said releasing part when independently actuated.

15. In a coin handling mechanism, a receptacle having compartment for coins of 75 different sizes, the compartments for coins of relatively the largest size being intermediately disposed between others of said compartments, an apertured hopper for receiving coins ejected from said receptacle, and means for ejecting said coins, other 80 than those of the largest size, separate means for ejecting the latter, said coins of largest size adapted when ejected to fall substantially directly through the aperture in said hopper, and mechanical means for discharging said hopper simultaneously with the 85 actuation of said separate ejecting means.

16. In a coin handling mechanism, a receptacle having compartments for coins of 90 different sizes, means for ejecting coins from said compartments, and a hopper having a sloping walled bottom leading to an aperture therein and having provisions for insuring that said ejected coins which may encounter said bottom, shall roll edgewise 95 downwardly thereover toward said aperture, one at least of said compartments being adapted to deliver substantially directly to said aperture, said hopper having further a closure for said aperture adapted to retain 100 said ejected coins.

In testimony whereof I have affixed my signature, in the presence of two witnesses.

CHARLES P. HIDDEN.
